GROOVING MACHINE

Filed Oct. 19, 1927

FIG 1

FIG 2

FIG 3

Andrew T. Butkey
INVENTOR.

BY C. Karpman
ATTORNEY.

UNITED STATES PATENT OFFICE

ANDREW T. BUTKEY, OF YOUNGSTOWN, OHIO, ASSIGNOR TO THE SAFETY PROCESSING COMPANY, A CORPORATION OF OHIO

GROOVING MACHINE

Application filed October 19, 1927. Serial No. 227,320.

This invention relates to grooving machines and more especially in machines used in making grooves in stair treads. Another object of the invention is to provide a device 5 that will work in making these grooves in varying materials such as wood, cement and stone.

A further object of the invention is to provide a device that will make a plurality of 10 grooves at the same time.

A still further object of the invention is to provide a device comprising two different means of making these desired grooves.

In the prevention of accident, it has been 15 found desirable to utilize means for preventing people from slipping on stair treads. It is the purpose of this invention to provide a device that will make a groove or a plurality of grooves in stair treads in order to provide 20 a place for pouring a plastic material into grooves which sets up hard with a rough and slightly uneven surface in order to provide means from keeping people from slipping while going up and down stairs.

25 With the foregoing and other objects in view which will appear as the description proceeds, the invention resides in the combination and arrangement of parts and in the details of construction hereinafter described 30 and claimed, it being understood that changes in the precise embodiment of the invention herein disclosed, can be made within the scope of what is claimed, without departing from the spirit of the invention.

35 The invention is illustrated in the accompanying drawings, wherein: —

Figure 1 is a side elevation of the device with parts broken away.

Figure 2 is a top plan view taken on the 40 line 2—2 of Figure 1.

Figure 3 is a detailed view showing a portion of Figure 1.

By referring to the drawings it will be seen 45 that I have provided a body portion 1 upon which is positioned a motor 2. This motor 2 is positioned on the top of the body portion 1 at the rear end of same. Ordinarily this motor will be energized by an electrical current. In order to move the device freely I 50 have provided a handle member 3 which is

used in moving the device back and forth in connection with supporting wheels 4 which are preferably made with rubber tires.

One of the means of making the desired 55 grooves is by a plurality of adjustable circular cutters 5 which are secured to a movable shaft 6 and manipulates by means of a fulcrum arms 7 functioning with a fulcrum shaft 8. In order to allow for up and down movement of the circular cutters 5 there has been provided a circular slot 9 formed in the side walls 10 of the body portion 1. In order to hold 60 the fulcrum arms 7 in fixed position there is provided an adjustable stop 11 which functions with a curved slot 12.

65 By referring to Figure 1 it will be seen that when the motor 2 has been put in motion a belt 13 provides driving power for the adjustable circular cutters 5. It will also be seen that there is a second belt 14 connected 70 to the motor 2 which functions with a drive pulley 15 secured to shaft 16 which also carries pulleys 17 and 18. The pulley 17 functioning with a belt 19 energizing a pulley 20 secured to a shaft 21 and carries a plurality 75 of kick off cams 22. These kick off cams 22 functioning with a plurality of perpendicular picker shafts 23 causing the same to move rapidly up and down as the perpendicular picker shafts are energized by the kick off 80 cams 22 and tension springs 24. The tension springs 24 are positioned around each perpendicular picker shaft 23. The lower end of each of the tension springs 24 are held by means of a seat 25 so that the tension springs 85 24 are held under desired tension. The lower ends 31 of said perpendicular picker shafts 23 are provided with bits 26 which may be formed to meet the varying conditions of the work to be done.

90 In order to keep the device moving forward when in operation the pulley 18 carries a belt 27 functioning with a pulley 28 which is carried upon a shaft 29. This shaft 29 is provided with a small friction wheel 30 which 95 functions with the outer circumference of the front supporting wheels 4. It is obvious that the small friction wheel 30 when functioning with the front support wheels 4, will allow for a slight pause in the forward movement 100

of the device to allow for the action of the bits 26.

It will be seen by referring to Figure 2 that the perpendicular picker shafts 23 and the circular cutters 5 are spaced apart so that as the device moves ahead each adjustable circular cutter 5 functions within a path partially formed by each perpendicular picker shaft.

In the construction of stair-ways it has been 10 found desirable to use strips of material which are placed within grooves for the purpose of preventing slipping and providing means which make it difficult or impossible to wear the treads smooth.

15 In order that the device may be guided along the stair tread as desired, I have provided adjustable guide arms 31 which function with a riser of the stairway.

What I claim is:

20 In a device of the class described, a body member, wheels carrying said body member, a movable horizontal shaft, a plurality of circular cutter members functioning on said movable horizontal shaft, a plurality of 25 spring tension perpendicular pickers positioned ahead of said cutters and so spaced apart that each picker is in alignment with each cutter, means for energizing said pickers and cutters.

30 In testimony whereof I affix my signature.
ANDREW T. BUTKEY.
